UNITED STATES PATENT OFFICE.

RICHARD HAHN, OF KEW GARDENS, NEW YORK.

DESIGN FOR AN EARRING.

Application filed June 30, 1927. Serial No. 22,623. Term of patent 7 years.

To all whom it may concern:

Be it known that I, RICHARD HAHN, a citizen of the United States of America, residing at Kew Gardens, in the county of Queens and State of New York, have invented a new, original, and ornamental Design for Earrings, of which the following is a specification, reference being had to the accompanying drawing, forming a part thereof.

In the drawing,

Fig. 1 is a side elevation.

Fig. 2 is an end elevation of an earring showing my new design.

I claim:

The ornamental design for an earring substantially as shown.

RICHARD HAHN.
